Inventor:
Joseph B. Strauss
by Rank & Cottrell

UNITED STATES PATENT OFFICE.

JOSEPH B. STRAUSS, OF CHICAGO, ILLINOIS.

BRIDGE.

Application filed December 10, 1921. Serial No. 521,305.

To all whom it may concern:

Be it known that I, JOSEPH B. STRAUSS, a citizen of the United States, residing at Chicago, in the county of Cook and State 5 of Illinois, have invented a certain new and useful Improvement in Bridges, of which the following is a specification.

This invention relates to bridges, and has for its object to provide a new and improved device of this description. The invention has among other objects to provide a construction where the counterweight is supported separate from the main span and arranged so that the supports for the 15 counterweight do not interfere with its movement when the bridge is opened and closed.

The invention has other objects which are more specifically set out in the following 20 description.

Referring now to the drawings

Fig. 1 is a view showing one form of bridge embodying the invention;

Fig. 2 is a view taken on line 2—2 of 25 Fig. 1;

Fig. 3 is a view taken on line 3—3 of Fig. 1;

Fig. 4 is a sectional view taken on line 4—4 of Fig. 3.

Fig. 5 is a rear elevation with parts omitted showing the relation of the counterweights to the supports;

Fig. 6 is a sectional view through the 35 counterweight showing the location of the metal counterweight frame members.

Like numerals refer to like parts throughout the several figures.

Referring now to the drawings I have shown a main span 1, pivoted at 1^a. Back 40 of the main span are two supports 2, located on opposite sides of the roadway. These supports may be of any desired structure. As herein shown they are of an A-frame construction. Pivots mounted upon these 45 supports is a counterweight frame 3. This counterweight frame is connected by the connecting members or links 4 with the main span.

The bridge is lifted and lowered by means of the operating struts 5 which are 50 connected with the main span as shown, and which are actuated by actuating mechanism on the supports 2. As herein shown the

struts 5 are provided with teeth which are engaged by pinion 5^a connected with a suitable source of power, such as a motor located 55 in the housing 5^b. The counterweight frame has the two side truss members, and there are preferably two links 4, and two operating struts 5 on opposite sides of the roadway. There are preferably two counterweights 6. These counterweights are pendant counterweights, and they may be connected with the counterweight frame in any desired manner. As herein shown the side members 60 of the counterweight frame are each provided with downwardly projecting members 7, which project partway into the counterweight. 65

The lower part of the counterweight is 70 provided with two portions opposed to each other and separated by a slot or space 8. Running along the sides of this space are metal members 9 extending upwardly, which are connected with the members 7 as shown, 75 the members preferably overlapping and being riveted or otherwise fastened together.

I prefer to make these counterweights of concrete, and the members 7 and 9 are embedded therein. The counterweights 6 are 80 in the plane of the supports 2, and the slots 8 in the counterweight are adapted to receive these supports when the bridge is opened so that they do not interfere with the movement of the bridge or the counterweights. 85

When the counterweights have been made solid as heretofore, it has been necessary to offset them with relation to the supports, and this means an expensive construction all of 90 which is avoided by the present construction.

If the counterweights are made solid, the operating struts 5 will also interfere with their movement, and hence to avoid this I provide slots or spaces 10 in the upper end 95 of the counterweight into which these operating struts are received as the bridge is being opened, so that there is no interference.

The spaces or slots 8 and 10 are preferably offset or out of alignment as clearly shown in Fig. 2. When the bridge is closed, the parts are as shown in dotted lines in Fig. 1. To open the bridge the pinions or gears 100

5^a are rotated, and these engage the teeth on the struts 5 and cause the main span to be lifted, the counterweights counterbalancing it in all its various positions. As the main span is lifted the counterweights move down and the supports 2 enter the spaces 8 therein, as shown in Fig. 1. The operating struts 5 enter the slots or spaces 10 during this movement. It will thus be seen that by this 10 construction the counterweights may be placed in alignment with the supports 2, and yet part of these counterweights project past these supports when the bridge is opened, without interfering with the movement of 15 the bridge and the counterweights. This very greatly decreases the cost of the construction, and particularly the construction necessary to support and carry the counterweights.

20 I have shown in detail a particular construction embodying the invention, but it is of course evident that the parts may be varied in many particulars, without departing from the spirit of the invention as embodied in the claims hereto appended, and I 25 therefore do not limit myself to the particular construction shown.

I claim:

1. A bridge comprising a main span, separate supports back of said main span, a counterweight frame mounted on said supports, a connection between said counterweight frame and said main span, counterweights connected with the said counterweight frame, each of said counterweights having opposed parts with a space between them into which are received said supports when the bridge is moved to its open position, whereby portions of the counterweight may move past said supports without interference.

2. A bridge comprising a pivoted main span, supports back of said main span and on opposite sides of the roadway, a counterweight frame mounted on said supports, a connection between said counterweight frame and said main span, an operating strut connected with said main span, actuating mechanism mounted on said supports for 45 actuating said operating strut to open and close the bridge, a counterweight connected with said counterweight frame, said counterweight having opposed portions separated by a space into which one of said supports is received when the bridge is open, said counterweight being also provided with opposed portions separated by a space into which said operating strut is received as the bridge is opened.

60 3. A counterweight for bridges slotted at its upper and lower ends, the slot at the lower end adapted to receive the supporting member for the counterweight, and the slot at the upper end adapted to receive an operating strut.

4. A counterweight for bridges slotted at its upper and lower ends, the slot at the lower end adapted to receive the supporting member for the counterweight, and the slot at the upper end adapted to receive an operating strut, said slots being out of alignment.

5. A bridge comprising a pivoted main span, separated supports back of said main span, located on opposite sides of the roadway, a counterweight frame mounted on said supports, a connection between said counterweight frame and said main span, two pendant counterweights connected with said counterweight frame and located on opposite sides of the roadway, said counterweights 75 provided with slots into which are received said supports when the bridge is opened.

6. A bridge comprising a pivoted main span, separated supports back of said main span located on opposite sides of the roadway, a counterweight frame mounted on said supports, a connection between said counterweight frame and said main span, an operating strut connected with said main span, actuating mechanism therefor carried by said supports, two pendant counterweights connected with said counterweight frame and located on opposite sides of the roadway, said counterweights provided with slots into which are received said supports when the bridge is opened, each of said counterweights provided with additional slots into which said operating struts are received.

7. In a bridge a counterweight frame exterior to the counterweight and separate from the bridge span and having projecting metal members, projecting at an angle from said frame, a counterweight connected with said members, the members projecting partway along the counterweight with an open space in the counterweight below the said members, two sets of side members connected with the counterweight below said projecting members and connected therewith.

8. In a bridge a counterweight frame, exterior to the counterweight and separate from the bridge span and a counterweight, a projecting member connected with the said frame and projecting at an angle from said frame and centrally partway through said counterweight, side members connected with said central member and with said counterweight, said side members separated by a space below said central member.

9. A bridge comprising a pivoted main span, separated supports back of said span located on opposite sides of the roadway, a counter weight frame mounted on said supports, a connection between the counterweight frame and the main span, two concrete counterweights, one on each side of the roadway, said counterweights having one end attached to the lower member of said counter weight frame and projecting down-

wardly therefrom so as to provide an open roadway space between them, means for holding said counter weights in rigid relation to the counter weight frame in all their various positions, each counter weight provided at its lower end with two separated parts with a space between them into which

said separated supports are received when the bridge is opened.

Signed at Chicago, county of Cook and ¹⁰ State of Illinois, this 6th day of December 1921.

JOSEPH B. STRAUSS.
